(Cl. D3—17)

FIG. 1

FIG. 2

Fig. 1 is a front view of a panty embodying my new design; and

Fig. 2 is a rear view thereof.

The dominant feature of my design resides in the panel of the specific configuration disclosed which extends down from the waist front, through the crotch and upwardly in the back toward the horizontal center line of the panty as shown.

I claim:

The ornamental design for a panty, as shown and described.
